(57) **CLAIM**

The ornamental design for a pendant, as shown and described.

DESCRIPTION

FIG. 1 is a front perspective view of a pendant showing my new design;

FIG. 2 is a front plan view of the pendant;

FIG. 3 is a back plan view of the pendant;

FIG. 4 is a side view of the pendant;

FIG. 5 is an opposite side view of the pendant;

FIG. 6 is a top view of the pendant; and,

FIG. 7 is a bottom view of the pendant.

The broken lines shown in the drawings represent portions of the pendant which form no part of the claimed design.
